UNITED STATES PATENT OFFICE

WALTER B. STEVENS, JR., OF NEW YORK, N. Y.

DOG-MUZZLE.

1,132,289.

Specification of Letters Patent. Patented Mar. 16, 1915.

Application filed August 3, 1914. Serial No. 854,763.

To all whom it may concern:

Be it known that I, WALTER B. STEVENS, Jr., a citizen of the United States, and a resident of New York city, in the county of New York and State of New York, have invented 5 certain new and useful Improvements in Dog-Muzzles, of which the following is a specification.

The invention relates to dog muzzles, and 10 it has for its object to provide a muzzle which, though constructed for a particular size of head, may be adjusted to fit a dog having a short nose or a dog having a long nose.

15 A further object of the invention is to connect the forward and rear nose members or arches of the muzzle by means of a more or less soft and flexible piece which will serve to increase the comfort of the animal to 20 which the muzzle is applied.

The nature of the invention will be best understood when described in connection with the accompanying drawings, in which—

25 Figure 1 is a perspective view of the improved dog muzzle, and Fig. 2 is a plan thereof.

Similar characters of reference designate corresponding parts throughout the several views.

30 Referring to the drawings, in which the invention is illustrated as embodied in a familiar type of wire muzzle composed of wire nose and jaw frames adapted to be secured to the head of a dog by means of 35 a suitable headstall of leather or other flexible material, 10 designates the front arch and 11 the rear arch of the nose frame or member which, together with the jaw frame 12, are constructed of wire of the proper 40 stiffness in well-known manner. For example, a piece of wire 14 is provided with an eye 15 at one end and is then extended upwardly and forwardly and bent over transversely at the top and then downwardly to

45 serve as a part of the rear arch of the nose piece. At the base of the arch, it is formed in a loop 16 and is then carried forwardly along one side of the muzzle the desired distance, bent upwardly at a suitable angle and

50 at the top carried transversely across the front of the muzzle with a loop 17 at each corner, whereupon it is turned downwardly at the same angle to complete the forward arch of the nose piece. After being carried

55 along the other side to the rear, where it is looped again to provide a second loop 18,

it is crossed transversely to the opposite side of the muzzle and secured thereto by a suitable eye 19. At the front of the muzzle a transverse base piece 21 is secured and dropped below the sides of the jaw frame 12, and to it is connected a longitudinal member 22 which is also connected to the rear transverse piece. Extending upwardly and substantially in the plane of the piece 21 is 60 an arch piece 23 whose ends are turned over the sides of the muzzle and which arch piece is fastened at the top to the rear arch piece constituting with it the rear nose piece or member of the muzzle. Suitable links or 65 rings 24 are hung in the loops 16 and 18 and through these passes a neck strap 25 which is provided with a suitable buckle 26 for adjustment.

No claim is made to the foregoing construction which is old and well-known and in which it has been the practice heretofore to rigidly secure the forward and rear arches or nose members together by some stiff and hard material as wire or sheet metal, a head 70 strap being secured to the rear arch. It is the object of the present invention to provide between the said front and rear portions of the nose member adjustable means, and which are preferably also more or less 75 soft, whereby the effective length of the muzzle may be varied to accommodate it to different lengths of noses. A particular size of muzzle may, therefore, be adapted to various dogs by merely adjusting the length 80 of the connection between the front and rear arches. This is effected in convenient manner by attaching to the forward arch one end of a strap 27, which may be of leather or other suitable material and preferably 85 somewhat soft and flexible and passing the said strap through a leather or metal chape 28 or other suitable holding or locking means therefor, the chape being placed beneath or above the tops of the rear arch 90 pieces and the strap brought respectively over or under the same. To further insure a firm hold, a pin 29 may be fixed to the top of the rear arch to fit suitable holes 30 of the strap. At its rear end, the strap 27 is provided with suitable holes 31 for adjusting 95 its length in connection with a buckle 32 secured to the top of the neck strap 25, the strap affording thus the head strap of the muzzle.

105 110 To adjust the nose piece, it is necessary merely to draw the forward arch piece,

which is sufficiently pliable or flexible for the purpose, toward the rear portion of the nose piece, as indicated in the position shown in dotted lines in Fig. 1, and take up the slack in the strap, or vice versa. Strap 27 is then secured by the chape 28 or the like.

The great majority of dog muzzles are made regardless of the shape of the dog's head and merely to standard sizes; but with 10 the improvements herein set forth incorporated, a muzzle though conforming to a particular size of head, may be made to fit comfortably on a dog of short nose or of long nose, which has heretofore not always 15 been the case. Moreover, in providing between the front and rear nose pieces a member which is to some extent at least non-rigid and soft, as for example of leather, the dog will be much more comfortable than when 20 provided with a muzzle of the character heretofore in use and employing stiff and hard material between said pieces.

I claim:

1. In a wire muzzle for dogs: a front normally fixed wire nose member and a rear wire nose member; an adjustable flexible member connecting said two nose members to effect an angular displacement of the plane of said front nose member relatively to said rear nose member; and means to lock said flexible member to said rear wire nose member.
2. In a wire muzzle for dogs: a front normally fixed wire nose member and a rear

wire nose member; a neck strap; a strap 35 connecting said front nose member with said rear nose member and with said neck strap to effect an angular displacement of the plane of said front nose member relatively to said rear nose member; and means co- 40 operating with the top of said rear wire nose member to lock said strap in position to maintain the adjustment.

3. In a wire muzzle for dogs: a front wire nose member and a rear wire nose member; 45 a strap secured to said front nose member to effect an angular displacement of the plane of said front nose member relatively to said rear nose member; and a chape coöperating with the top of said rear nose member and 50 through which said strap is adapted to pass.

4. In a wire muzzle for dogs: a front wire nose member and a rear wire nose member; a strap secured to said front nose member to effect an angular displacement of the plane 55 of said front nose member relatively to said rear nose member; a chape coöperating with the top of said rear nose member and through which said strap is adapted to pass; and a neck strap provided with a buckle to 60 receive the end of said strap.

Signed at New York in the county of New York and State of New York this 30th day of July A. D. 1914.

WALTER B. STEVENS, JR.
